UNITED STATES PATENT OFFICE.

JOHN BROWN, OF NORWOOD, MASSACHUSETTS, ASSIGNOR TO LOUIS C. SMITH, OF BROOKLINE, MASSACHUSETTS.

GLUING-MACHINE.

SPECIFICATION forming part of Letters Patent No. 698,791, dated April 29, 1902.

Application filed April 1, 1901. Serial No. 53,777. (No model.)

To all whom it may concern:

Be it known that I, JOHN BROWN, a citizen of the United States, residing at Norwood, county of Norfolk, State of Massachusetts, (whose 5 post-office address is No. 23 Williams street, Norwood, Massachusetts,) have invented an Improvement in Gluing-Machines, of which the following description, in connection with the accompanying drawings, is a specification, 10 like numerals of the drawings representing like parts.

My invention has for its aim the production of a novel machine or apparatus for gluing the facing or covering upon the boards of book-covers; and the invention comprises a 15 suitable support having at one end a gluing mechanism and at the other end a pressing mechanism combined with an endless feed-apron, which is adapted to carry the sheets of material which form the facing or covering of the book-covers through and away from the gluing mechanism in order that the said sheets may have glue spread upon one side thereof, and the said feed-apron is also adapted 20 to feed to the presser mechanism, which is preferably in the form of squeeze-rolls, the said glued sheets of material and the backing or the boards of the book-cover to which the said glued sheets are to be applied, the 25 30 said presser-rolls pressing the covering or facing firmly upon the boards of the book-cover and causing the same to adhere thereto.

The gluing mechanism comprises a glue-receptacle which is detachably mounted upon a support and the bottom of which is formed by a distributing-roll and a pair of spreading-rolls, said rolls being mounted for rotation in the support, means being provided to 35 40 rotate the distributing-roll at a different speed from the spreading-rolls. Preferably the glue-receptacle will be surrounded by a water-jacket, and means will be provided to heat the water in the jacket, thereby operating to keep the glue warm and in a liquid state.

In the operation of the device the attendant will feed the sheets of material which are to form the facing or covering of the boards of the book-cover to the feed-apron in front 45 50 of the distributing-roll, and as the sheet is carried by the apron underneath the roll the

said roll deposits a thin film of glue or other adhesive upon the upper face of the sheet of material. As the apron delivers the sheet from the distributing-roll the attendant takes 55 the said sheet and applies the same to the outside faces of the boards of the book-cover, turning in the sheet around the corners of the book-covers, as usual. The book-cover with the facing thus applied thereto is again 60 placed upon the feed-apron, which delivers it to the presser-rolls, where the facing is firmly pressed and made to adhere to the book-covers, the pressure of the roll causing the facing to be smoothly laid upon the book- 65 covers.

Referring to the drawings, Figure 1 is a vertical section of my machine on the line *xx*, Fig. 2. Fig. 2 is a front elevation of the machine with a portion of the glue-receptacle 70 shown in section. Fig. 3 shows the driving-roll for the feed-apron, and Fig. 4 is a detail hereinafter described.

The machine is supported upon any suitable frame or support, said frame comprising 75 the platform 3, having near one end the uprights 4, on which is supported the gluing mechanism, and at the other end suitable uprights 5, in which the pressing mechanism is sustained.

The gluing mechanism comprises the glue-receptacle 6, which extends across the machine and which is preferably detachably secured to the upper ends of the standards 4, as by screws 7, (see Fig. 2,) the object in 85 making the said receptacle removable being so that it can be detached from the machine and washed whenever it is necessary to do so. The bottom of the glue-receptacle is formed by the distributing-roll 8 and the pair of 90 spreading-rolls 9, the said spreading-rolls being arranged one either side of the distributing-roll and contacting with the said roll, the lower edge of the sides of the receptacle contacting with the upper surface of the spreading-rolls, as seen in Figs. 1 and 2.

The sheets of material are fed past the gluing mechanism by means of a feed-apron 10, said feed-apron passing around and being driven by a driving-roll 11, which is supported in boxes 12, adjustably mounted in the standards 4. A set-screw 13 is used to adjust

8c

100

the feed-roll 11, as desired. The feed-roll may be driven by any suitable mechanism, and, as shown in Fig. 2, the end of the shaft of said roll has mounted thereon a loose pulley 14, 5 connected to any source of motive power, and any suitable clutch mechanism 15 may be provided for clutching the loose pulley 14 to the shaft of the feed-roll 11, said clutch being operated in any suitable way, as by foot-treadle 10 16. The shaft of the feed-roll has fast thereon a suitable gear 17, which meshes with a gear 18 on the end of the shaft of the distributing-roll 8, (see Fig. 2,) whereby the said distributing-roll is driven from the feed-roll, 15 the gears 17 and 18 being of the same size, so that the surface speed of the feed-apron and the distributing-roll will be the same. The spreading-rolls 9 are driven from the distributing-roll 8 and at a different surface or angular velocity, and for this purpose I preferably provide one end of the said distributing-roll with the small gear 20, which meshes with the larger gears 21 on the end of the spreading-rolls 9, by reason of which construction 20 it will be seen that the rotation of the distributing-roll causes the spreading-rolls to rotate in an opposite direction from said distributing-roll, but at a reduced speed, so that there is a rubbing action between the surfaces of the 25 distributing-roll and the spreading-rolls. The distributing-roll, therefore, is allowed to carry down only a thin film of the glue or other adhesive contained in the receptacle 6, and such thin film is deposited upon the upper 30 surface of the facing of the sheet of material which is fed to the distributing-roll by the endless apron 10. In order to prevent the said sheet of material from adhering to the distributing-roll and from being lifted off of the feed-apron, I have provided a series of yieldably-mounted clearing-fingers 23, having pointed ends and preferably having at such ends curved surfaces 24, which fit the roll, the points of said fingers preventing the 35 sheet of material from adhering to the distributing-roll 8. One convenient way of mounting these fingers is illustrated in Fig. 1, where-in the standards 4 are provided with arms 25, which support a cross-piece 26, having a series of depending arms 26', to which are pivotally connected the said fingers 23, springs 27 being provided to yieldably hold said fingers against the distributing-roll. In order to keep the surface of the roll clean, I have 40 provided the scraper 30, said scraper being illustrated as a bar extending across and contacting with the upper side of the distributing-roll 8 and having the upturned slotted arms 31 at either side, said arms being adjustably secured to the ends of the receptacle 6 by any suitable means, as by bolts 33. By making the scraper adjustable its constant contact with the surface of a distributing-roll may be preserved. 45 The glue-receptacle 6 is preferably surrounded at its upper end by a water jacket or chamber 40, and underneath said chamber

is provided a series of gas-jets 41 for heating the water in the said chamber, and thus keeping the glue in a liquid state. Pivoted 70 to the lower end of the water-jacket are wings 42, said wings serving to protect the gas-flame and prevent the same from becoming extinguished. A glass gage 43 may be provided, if desired, for readily ascertaining the water-level in the water-jacket, and an upper opening 44 through the top of the water-jacket may be provided for the escape of steam. 75

The upper end of the glue-receptacle has 80 detachably mounted therein a suitable screen 45, in order that as the glue or other adhesive is poured into the receptacle any lumps or foreign matter may be strained out.

The presser mechanism comprises two presser-rolls 50 51, mounted for rotation in 85 the standard 5, the roll 51 being yieldingly held against the fixed roll 50 by the springs 52, the tension of which may be adjusted by the adjusting-screw 53, as usual in devices of this class. 90

As stated above, the feed-apron 10 operates not only to feed the sheets of material to the distributing-roll 8, in order that the glue or other adhesive may be applied thereto, but also operates to feed to the presser-rolls the 95 glued sheets and the backing to which said sheets are to be applied. For this purpose the feed-apron passes over the guide-roll 55, down through a slot 56 in the platform 3, over the direction-rolls 57 58, and up through a 100 slot 59 in the platform and over the direction-rolls 60 and 61, the last roll being situated adjacent the presser-rolls 50 and 51, as seen in Fig. 1. The apron is then taken over direction-roll 62 and down through the platform over rolls 63 64, and thence up through 105 the platform and to the driving-roll 11.

This embodiment of my invention is illustrated as adapted to apply the covering or facing to book-covers, and in the operation of 110 the device the attendant feeds the sheet of material which is to form the facing or covering of the book-cover to the distributing-roll 8, with the outside surface of said facing or covering resting upon the feed-apron 10. 115 The distributing-roll operates, as above described, to deposit a thin film of adhesive on the upper face of said covering or facing. As the apron 10 delivers the glued sheet of material from the distributing-roll the attendant takes the same and applies it to the boards of the book-covers, the edges of the facing being turned in, as usual, and then the said attendant will deposit the book-covers upon the portion 10' of the feed-apron, the said 120 apron operating to feed the book-covers to the presser-rolls 50 51, which operate to firmly press the facing or covering onto the boards of the book-cover and cause them to adhere thereto in a smooth condition. As the book-covers thus finished are delivered from the 125 presser-rolls they drop onto a platform 300, where they may be removed by an attendant. By carrying the feed-apron underneath a

portion of the platform, as at 3', I provide a convenient place for the attendant to work in roughly applying the facing or covering to the boards of the book-covers and turning in 5 the edges thereof.

Any suitable means for driving the presser-rolls 50 and 51, which of course are geared together, as usual, may be employed. As one convenient way of accomplishing this, I have 10 shown the lower presser-roll 50 as being belted to the direction-roll 61 by the belt 70.

It is desirable to keep the feed-apron clean, and for this purpose I preferably provide two 15 rotary brushes 71, which may be driven by means of belts 72 from the direction-rolls 63 and 64.

The apron 10 is illustrated as being composed of a series of parallel endless bands, there being three such bands shown in this 20 instance, 10^a 10^b 10^c, and the driving-roll 11 and the direction-rolls above referred to will each have the annular ribs or spacing-flanges 90 for the purpose of spacing the sections of the feed-apron and guiding the same. The 25 ribs 90 on the driving-roll 11 will preferably project beyond the surface of said roll a distance just equal to or slightly less than the thickness of the feed-apron 10, so that the ribs on said driving-roll will form with the 30 sections of the feed-apron a practically smooth supporting-surface for the sheets of material as they are fed between the feed-apron and distributing-roll.

Preferably the front portion of the platform 35 3 will be provided with a pocket 80, which is preferably situated directly underneath the driving-roll 11, said pocket serving as a useful place for the placing of any tools that are to be used in connection with the machine.

40 While I have described my device as particularly adapted to the applying of sheets of facing or covering material to the boards of book-covers, yet it is evident that my invention is not limited to this use, but may be 45 used whenever it is desired to apply a coating of glue to one face of a sheet of material and then apply said glued sheet to a backing.

Various changes may be made in the structure of the device without departing from the 50 spirit of my invention, and I therefore reserve the right to make such changes as come within the scope of the appended claims.

Having described my invention, what I claim as new, and desire to secure by Letters 55 Patent, is—

1. In an apparatus of the class described, a support, a glue-receptacle detachably carried thereby, a hot-water jacket surrounding said receptacle, a distributing-roll, and a plurality 60 of spreading-rolls mounted for rotation in said support, said rolls being independent of the glue-receptacle and forming the bottom thereof when said receptacle is in its operative position, a pair of presser-rolls, an endless feed-65 apron having its face closely adjacent the distributing-roll, means to operate said presser-rolls and feed-apron in unison, said apron

operating to feed sheets of material past said distributing-roll and also to feed the glued sheets and the backing to which they are to 70 be applied to the said presser-rolls, and a plurality of rigid clearing-fingers engaging the delivery side of said distributing-roll, and springs to yieldingly hold said fingers in contact with the said roll. 75

2. In an apparatus of the class described, a support, a glue-receptacle detachably carried thereby, a hot-water jacket surrounding said receptacle, a distributing-roll, and a plurality 80 of spreading-rolls mounted for rotation in said support, said rolls being independent of the glue-receptacle and forming the bottom thereof when said receptacle is in its operative position, an endless feed-apron for feeding sheets of paper past said distributing-roll, means 85 for driving said apron a series of pivotally-mounted clearing-fingers engaging the delivery side of said delivery-roll, springs to yieldingly hold said fingers in contact with the roll, and a substantially U-shaped scraper in 90 said receptacle and bearing on the top of the distributing-roll, the upwardly-extended arms of said scraper being adjustably secured to the opposite sides of the receptacle.

3. In an apparatus of the class described, a 95 glue-receptacle, a hot-water jacket surrounding the same, a distributing and spreading rolls forming the bottom of said receptacle, means to drive said rolls, a pair of presser-rolls, and an endless feed-apron adapted to 100 feed sheets of material past said distributing-roll, and to feed the glued sheet and the backing to which it is to be applied to the presser-rolls.

4. In an apparatus of the class described, a 105 glue-receptacle, a water-jacket surrounding the same, burners located beneath said jacket, said jacket having wings pivoted to its lower edge, said wings operating to protect the flame of the burner, a distributing-roll and spreading-rolls forming the bottom of said receptacle, means to drive said rolls, and means to feed sheets of material to said distributing-roll. 110

5. In an apparatus of the class described, a 115 glue-receptacle, an annular water-jacket surrounding the same, burners extending around the glue-receptacle and located beneath said jacket, wings pivoted to the lower edge of said jacket and protecting the burners, glue-distributing means, and means to feed the sheets of material to said glue-distributing means. 120

6. In an apparatus of the class described, a frame comprising a suitable platform having standards at one end, a glue-receptacle mounted on said standards, a distributing-roll and spreading-rolls rotatably mounted in said standards and forming the bottom of said glue-receptacle, a pair of presser-rolls rotatably mounted at the other end of said platform, and a feed-apron adapted to feed sheets of material past the distributing-roll, and to feed the glued sheet, and the backing to which it is to be applied, to the presser-rolls, said 125 130

apron being carried beneath the central portion of the platform, whereby the said central portion is accessible.

7. In an apparatus of the class described, a support, a distributing-roll, and spreading-rolls mounted for rotation therein, a glue-receptacle detachably carried on said support, said distributing and spreading rolls forming the bottom of said receptacle but being independent thereof, an annular hot-water jacket surrounding said receptacle, presser-rolls, an endless feed-apron having the face thereof closely adjacent to the surface of the distributing-roll, said apron operating to feed sheets of material past the distributing-roll, and the glued sheets and the backing to which they are to be applied to the presser-rolls.

8. In apparatus of the class described, a platform, a glue-distributing device at the side of said platform, a pair of presser-rolls detachably mounted at the other end of said platform, and a feed-apron adapted to feed sheets of material past the glue-distributing device, and to feed the glued sheet and the backing to which it is to be applied to the

presser-rolls, said apron being carried beneath the central portion of the platform, whereby the said central portion is accessible.

9. In apparatus of the class described, a platform, a glue-distributing device at the side of said platform, a pair of presser-rolls detachably mounted at the other end of said platform, and a feed-apron adapted to feed sheets of material past the glue-distributing device, and to feed the glued sheet and the backing to which it is to be applied to the presser-rolls, said apron being carried beneath the central portion of the platform, whereby the said central portion is accessible, combined with brushes for cleaning the feed-apron, said brushes being located beneath the central portion of the platform.

In testimony whereof I have signed my name to this specification in the presence of two subscribing witnesses.

JOHN BROWN.
